(57) **CLAIM**

The ornamental design for a wireless internet router, as shown and described.

DESCRIPTION

FIG. 1 is a front perspective view of a wireless internet router showing our new design;

FIG. 2 is a rear perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof; and,

FIG. 8 is a rear elevational view thereof.

The broken line showings of the ventilation holes, ports, display screen, and indicia are for the purposes of illustrating portions of the wireless internet router and form no part of the claimed design.
